UNITED STATES PATENT OFFICE

HERMAN C. HEATON AND FRANK H. ARMSTRONG, OF CHICAGO, ILLINOIS, ASSIGNORS
TO LINK BELT COMPANY, OF CHICAGO, ILLINOIS, A CORPORATION OF ILLINOIS

HYDRAULIC CLAMP FOR ROTARY CAR DUMPERS

Application filed May 7, 1928. Serial No. 275,594.

Our invention relates to improvements in rotary car dumpers and has for one object to provide a new and improved type of dumper wherein the car is held in place in the dumping cradle during rotation by means of hydraulically operated top clamps.

One object of the invention is to provide a new and improved form of holding clamps wherein no brakes, counterweights or additional holding devices are needed to hold the car in place on the cradle. Another object is to provide a hydraulic clamp operating mechanism. Our invention is illustrated more or less diagrammatically in the accompanying drawings, wherein—

Figure 1 is a side elevation;

Figure 2 is a section on line 2—2 of Figure 1;

Figure 3 is a section on line 3—3 of Figure 1;

Figure 4 is a section along the same line as Figure 3 but showing the cradle in the car dumping position;

Figure 5 is a detail, part in elevation and part in section, of the valve and control mechanism for one of the clamps;

Figure 6 is an enlarged detail view of ratchet and pawl arrangement for holding the car;

Figure 7 is a detail showing the operating cams and levers.

Like parts are indicated by like characters throughout the specification and drawings.

In general, our car dumper is equipped with eight separate cast-steel clamps, carried by the cradle, four on each side of the car. Each clamp is moved along guides by means of a piston rod and piston, the latter operating in a steel cylinder rigidly secured to the structural steel frame-work of the car dumper cradle. The pistons are moved to raise and lower the clamps by a hydraulic fluid supplied under pressure to each cylinder by a small electrically driven pump mounted on the cradle. The pump draws the fluid from a suction or supply tank, discharging it through a pipe to a control valve which distributes the hydraulic fluid through pipe lines to both ends of the cylinders, as desired, to move the pistons down or up as

the case may be. The fluid discharged from the cylinders is returned to the suction or supply tank for using over and over. The location and shape of the supply tank is such that the pump inlet or suction is always submerged in the fluid, even when the cradle is rotated its maximum excursion, or approximately 180° from its initial or upright position. Since the pump is a centrifugal and not a positive displacement type, it runs continuously when operating the dumper, thus maintaining a pressure on the control valve at all times. The control valve is operated automatically by a valve lever which engages a fixed cam track on the dumper foundation, and thereby controls the movements of all clamps in response to the rotation of the cradle.

In the initial or starting position of the cradle the clamps are in the raised position at a point above the maximum height of any car which may be dumped by the dumper. The control valve is held in the central position, closing the ports to both the upper and lower ends of the cylinder by means of a centering device. After the cradle has rotated through an angle of approximately 10° the valve lever, which is mounted on and rotates with the cradle, engages the fixed cam track and moves the valve lever to one side, admitting fluid under pressure from the pump to the top of the cylinders and permitting escape of fluid from the bottom of the cylinders, thereby causing the hydraulic pressure to draw the clamps down to engage the top of the car. The cam track is so positioned as to hold the valve open to cause pressure to be continuously applied to the holding sides of the pistons until the valve lever runs off the track after excursion of approximately 90° from its starting position. The centering device then goes into operation, centers the valve lever, and closes all ports to and from the cylinders, thereby locking the clamps against movement in either direction and causing them to support the weight of the car and its contents as the cradle rotates further into the dumping position.

On the return movement of the cradle with the empty car at an angle of about 85° from

the initial position, the valve lever again engages the cam track, but since the cradle is rotating in the opposite direction the lever is moved in the opposite direction, opening the ports leading from the holding side of the cylinders to the suction or storage tank and opening the ports leading to the lifting side of the cylinders connecting with the pump. The hydraulic pressure thus is able to raise the clamps from the car and moves them to their initial or uppermost position. At approximately 10° from vertical, the valve lever disengages the cam track, allowing the centering device to again move the valve to its central position and lock the clamps in the upper or released position.

As a precaution against accident due to breaking of a fitting or pipe, some or all of the clamps, preferably the four at the ends of the cradle, are also equipped with mechanically operated pawls. These pawls are pivoted on the clamp guides and are adapted to be thrust into engagement with racks on the backs of the clamps by means of heavy springs, counterweighted levers, etc., which go into operation only after the clamps are seated on the car at about the time when the valve lever is returned to its central position as the cradle approaches the dumping position.

These pawls are forced out of engagement with the racks by means of a cam lever and cam track system similar to that used for operating the control valve.

The cradle is rotated by means of cables wound about and anchored on the roller rings, the bight of the cable being wound about motor driven drums whereby the cradle may be moved toward and from the dumping position.

A is the foundation for a receiving hopper A¹ into which the cars to be unloaded may be dumped. Carried on the foundation are a plurality of pillow blocks A². Pivoted on each pillow block is an equalizing frame A³ and journaled in each equalizing lever are a pair of rollers A⁴. The cradle has a roller ring A⁵ at each end of the cradle. These roller rings are supported by and are free to rotate on the rollers A⁴. Joining these roller rings is a bridge or frame work A⁶ which forms the body of the cradle. A⁷ are abutments, two on each roller ring; slideable in each abutment are take-up rods A⁸ supported by springs A⁹. The cable A¹⁰ is anchored at both ends by the take-up rods A⁸, extends around the flange A¹¹ of the roller ring and intermediate its ends is wound about the drum A¹². Each drum is rotated by a gear train A¹³ from a shaft A¹⁴. This shaft is driven through a reduction gear A¹⁵ by an electric motor A¹⁶. This motor may be controlled in any suitable manner to start, stop and reverse it to control the rotation of the cradle. A¹⁷ is the solenoid brake, automati-

cally controlled by electric current to the motor, whereby the cradle may be locked in position when the current is shut off from the motor.

B is the transversely movable transfer table having rollers B¹ adapted to travel on tracks B² on the cradle. B³ are springs normally yielding, forcing the transfer table toward the left as shown in Fig. 2. B⁴ is an abutment on the foundation, at each end of the cradle. At each end of the transfer table is a lug B⁵ carrying a roller B⁶ adapted to engage the abutment B⁴ when the cradle is in the upright position to compress the springs B³ and hold the transfer table in its initial position. As the cradle moves in counter-clockwise direction away from the upright toward the dumping position the springs B³ force the transfer table toward the left until the car B⁷ on the tracks B⁸ has moved, by the combined influence of the springs B³ and the force of gravity, into a position such that the side of the car engages the block B⁹ on the side of the cradle; reference to Fig. 4 will show the car in such position. Further rotation of the cradle causes the roller B⁶ to be raised out of engagement with the abutment B⁴. On the return movement the operation is the reverse and engagement of the roller B⁶ with abutment B⁴ forces the transfer table back to its initial position.

Arranged on opposed sides of the cradle are horizontal clamp guides C, C¹. Movable horizontally along the guides C are clamps C², C³ and along the guides C¹ are clamps C⁴, C⁵. In so far as their clamping effect is concerned, the clamps C², C⁴ and C³, C⁵ are identically the same, the only difference being that the clamps C², C³ have upward extensions C⁶ associated with the longer guides C for a purpose hereinafter to appear. The clamps C³, C⁵ have relatively short overhanging, car-engaging shoulders C⁷. These shoulders are short because the left-handed side of the car is always in engagement with the cushion B⁹ and, no matter how wide the car is, the clamp shoulder needs to be only wide enough to overhang the side of the car. The clamps C², C⁴, however, have relatively wide car-engaging clamping shoulders C⁸, these being necessitated by the fact that the position of the side of the car engaged by them varies with the width of the car and it is necessary that they be long enough to overhang and hold the narrowest car which is likely to be spotted on the cradle.

Associated with each of the clamps is a hydraulic cylinder C⁹, there being one for each clamp. Each cylinder contains a piston C¹⁰, driving a piston rod C¹¹ which operates one clamp, there being a knuckle joint C¹² interposed between the piston rod, a clamp to take care of any inaccuracy, expansion, contraction or play of the structure

and to prevent binding. C^{13} is a packing gland through which the piston rod travels as it projects from and is withdrawn into the cylinder.

D is a suction tank or reservoir. Associated with it is an electrically operated pump D^1 adapted to draw hydraulic motive fluid from the tank through the pipe D^2 . The tank D is supported on brackets D^3 , D^4 , and is always substantially full, as therefore, the intake of the pipe D^2 is always below the level of the fluid in the tank, independent of the angular position of the cradle, so that the pump is able to draw motive fluid from the tank at all times during the operation of the dumper. This pump is preferably a centrifugal and not positive displacement pump, and therefore when the dumper is being operated the pump is always in operation. The pump discharges motive fluid under pressure through the pipe D^5 to the control valve housing D^6 . This valve housing contains a slidable piston valve D^7 . The pipe D^5 discharges into the housing through a port D^8 intermediate the two ends of the piston valve. The ends of the cylindrical valves seat discharge through pipes D^9 , D^{10} to a return pipe D^{11} , which in turn discharges to the tank D at a point above intake end of the pipe D^2 . D^{12} is the breather pipe for the tank. The piston valve D^7 is controlled by the valve stem D^{13} extending out through a packing gland D^{14} in the elbow of the pipe D^{10} . It will be noted that the pipes D^5 , D^{10} , D^{11} through which motive fluid travels from the valve to the reservoir at low pressure are each larger than the pipe D^5 through which motive fluid travels from the pipe to the valve in high pressure.

Leading from the upper end of each of the cylinders C^9 is the relatively small high pressure pipe E . Each of these pipes extends downward along the cylinder and communicates with the piping E^1 , which piping in turn communicates with a main pressure pipe E^2 extending along the cradle. This main pipe is located at one side of the cradle only, so that the pipe system E^1 leading from it to the pipes E has elements of various length to communicate with the pipes associated with the cylinders on the far side of the cradle. This pipe E^2 communicates by means of a nipple E^3 with the port E^4 in one end of the valve cylinder. E^5 is a port at the other end of the valve cylinder communicating with a relatively large pipe E^{15} , from which lead branches, one to the lower end of each of the cylinders. It will be noted that thus there are two piping systems communicating, respectively, with the upper and lower ends of the cylinders and with opposed ends of the piston valve seat. The pipes communicating with the upper ends of the cylinders are smaller than those communicating with the

lower ends, the reason for this being that the maximum pressure is maintained in the upper ends of the cylinders to force the pistons down and hold the clamps against the top of the car to hold the car and its contents. While this is going on exhaust takes place through the large exhaust pipes, and, since the pipes are large, free exhaust travel of the hydraulic fluid from the lower ends of the cylinders may take place. When movement in the opposite direction occurs the pressure is reduced, because it only needs to be great enough to raise the clamps; thus the pipes which receive the exhaust on the lowering movement and carry pressure on the raising movement only can be made larger. When the parts are in the position shown in Fig. 5, both ports E^4 and E^5 are closed and the hydraulic fluid in the system cannot circulate. Thus the pistons are positively held in the definite position they may have occupied at the time the valve moved to the closed position. If the valve is now moved to the right in Fig. 5, motive fluid will be forced by the pump through the pipe D^5 into the port D^8 , thence longitudinally along the valve seat to the port E^4 , thence through the pipes E^2 , E^1 and E to the upper end of each cylinder. At the same time an exhaust path is opened through the lower ends of each cylinder, through the pipes E^{15} and the port E^5 , thence through the pipes D^{10} , D^{11} to the reservoir D , to replace the motive fluid drawn therefrom by the pump. This results in moving each piston downwardly until each individual clamp separately or simultaneously seats on the car. As soon as each clamp is seated, no further movement of the valve piston involved will take place and each clamp will be forced down against the car by a pressure which may be measured in terms of the effective cross-sectional area of the piston multiplied by the hydraulic pressure. After all the clamps have seated and the pistons have ceased movement, the centrifugal pump will continue to operate, maintaining the pressure in the system but not displacing any additional hydraulic fluid.

Some time thereafter the valve will be returned to the central position, but now the pistons will be in a position lower than that shown in Fig. 5, depending upon the height of the car. When the clamps are to be released the piston valve will be moved to the left in Fig. 5. The pump will then discharge motive fluid through the pipe D^5 , port D^8 and pipes E^{15} to the lower ends of the cylinder and motive fluid will be exhausted from the upper ends of the cylinder through the pipes E , E^1 , E^2 , E^3 , port E^4 , pipes D^9 to the reservoir D , and this will continue until the pistons have been moved back to the upper position as shown in Fig. 5, with the clamps raised. Continuing the pump operation will merely maintain the pressure in the system.

and hold the pistons in the upper position until the valve is again brought to the central position locking clamps away from the car.

The valve stem D^3 is reciprocated by means of a connecting shaft F , which extends across the cradle as indicated and is pivoted on a lever F^1 , mounted on the shaft F^{10} , which carries at one end the control lever F^{12} . This lever is balanced between tension springs F^2 , F^3 anchored on abutments F^4 , F^5 on the cradle. The results of these two springs is to center the control lever and likewise the valve, the position of the lever in Fig. 3 corresponding to the position of the valve shown in Fig. 5. If now the cradle is moved in a counter-clockwise direction from the position shown in Fig. 3, the lever F^{12} will be rotated in a clockwise direction by engagement of the roller F^4 with the cam track F^6 and the lever will be maintained in that position with the valve position to the right in Fig. 5 to permit motive fluid to be supplied to the cylinders to draw them down as long as the cam lever and roller F^4 remains in contact with the track. As soon as the cam lever and roller travels off the track the valve will be automatically returned to the neutral position, preventing circulation of the motive fluid and holding the clamps in the down position. On the return movement the roller F^4 will engage the cam track F^6 from the opposite direction and will be moved in counter-clockwise direction, thus moving the piston valve to the left and permitting such a distribution of the motive fluid as will cause the hydraulic pressure to raise the clamps, thus continuing until the control lever and roller F^4 runs off the track and the centering mechanism brings the valve back to the neutral position.

The relative positions of the lever F^{12} and roller F^4 which control the piston valve D^7 are shown in Fig. 7.

G is a saw-tooth ratchet on the back side of the long clamps at the ends of the cradle. G^1 is a lever pivoted on the clamp side, having at its end a dog G^2 adapted to engage the ratchet. G^3 is a compression spring associated with a guide pin G^4 to a yieldingly held latch in engagement with the ratchet. G^5 is a lever pivoted on the shaft G^{15} , said lever being connected by the link G^6 with the lever G^1 by a loose connection yoke and pin G^7 as indicated. Mounted on one end of the shaft G^{15} is a lever G^{16} pivotally connected to a control rod G^8 which extends down along the guide to engage at its other end one arm of the lever G^9 , which lever carries a roller G^{10} adapted to engage the cam track G^{12} . In the upright position of the cradle the roller G^{10} is in engagement with the cam track G^{12} . It will be understood that the spring G^3 tends to force the latch into engagement with the ratchet. The roller G^{10} as the cradle moves toward the dumping position is in contact

with the track G^{12} for a predetermined distance. Thus the ratchet and latch are disengaged when clamp movements commence. The roller G^{10} engages the track G^{12} and the roller F^4 engages the track F^6 and leave their tracks simultaneously at the time the hydraulic valve is moved to neutral position. The dogs G^2 at the right in Fig. 2 are operated by means of the lever G^{16} associated with the lever G^9 and the connecting rod G^{14} connected by means of a bell crank lever to the control rod G^8 . If, for any reason, the hydraulic system should become defective after the clamps C^2 , C^3 are seated upon the car and the piston valve D^7 is in neutral position, the latches G^2 engaging the ratchet G will lock the clamps which hold the car in the dumping position until on the return movement the roller G^{10} engages the cam track G^{12} .

We claim:

1. In a car dumper, a cradle and means for rotating it, a plurality of car holding clamps thereon and hydraulic means for moving them toward and from the car and for holding them in car clamping and in released positions, said hydraulic means including a separate hydraulic cylinder and piston for each clamp and a pump, a distribution valve, a pressure conduit leading from pump to valve, conduits leading from the valve to both ends of the cylinders and means responsive to the position of the cradle for operating the valve to displace it to distribute fluid under pressure to one end of the pistons, and permit flow of exhaust fluid from the other ends of the pistons to move the clamps and the valve operating means comprising a fixed cam track adjacent the cradle and a valve displacing means adapted to be engaged by the cam track during a portion of the cradle movement and means for automatically centering the valve when the valve displacing means are out of engagement with the cam.

2. In a car dumper, a cradle and means for rotating it, a plurality of car holding clamps thereon and hydraulic means for moving them toward and from the car and for holding them in car clamping and in released positions, said hydraulic means including a separate hydraulic cylinder and piston for each clamp and a pump, a distribution valve, a pressure conduit leading from pump to valve, conduits leading from the valve to both ends of the cylinders and means responsive to the position of the cradle for operating the valve to displace it to distribute fluid under pressure to one end of the pistons, and permit flow of exhaust fluid from the other ends of the pistons to move the clamps and for moving the valve into neutral position to close both the intake and exhaust passages from the cylinders to positively lock the clamp in place, and the valve operating means comprising a fixed cam track adjacent the cradle and a valve displacing means

adapted to be engaged by the cam track during a portion of the cradle movement and means for automatically centering the valve when the valve displacing means are out of engagement with the cam.

- 5 3. In a car dumper, a cradle and means for rotating it, a plurality of car holding clamps thereon and hydraulic means for moving them toward and from the car and for holding them in car clamping and in released positions, the hydraulic means comprising a cylinder and plunger for each clamp, the hydraulic system including a single storage reservoir motor driven pump and distribution valve and pipes leading from the distribution valve to both ends of the cylinders, the hydraulic means comprising a reservoir, the pump drawing hydraulic fluid therefrom, a distribution valve, pipes leading therefrom 10 to the cylinders, the reservoir being positioned on the cradle at a point generally above the intake of the pump, the port through which material passes from the reservoir to the pump being located at a point with 15 respect to the reservoir position that as the reservoir and pump rotate with the cradle toward the dumping position, the liquid level in the reservoir is moved progressively higher and higher, an increased proportion 20 of the reservoir being raised above the discharge port being such that the pump intake is submerged at all times independent of cradle position.
